United States Patent

Des. 234,414
Patented Mar. 4, 1975

234,414

FOLDING CHAIR

Yvon Becquet, La Rochelle, France, assignor to Societe
SO-GE-MA-P, La Rochelle, France

Filed June 15, 1973, Ser. No. 370,406

Term of patent 14 years

Int. Cl. D6—01

U.S. Cl. D6—73

Fig-2

FIG. 1

FIG. 2

FIG. 3

FIG. 1 is a perspective view of a folding chair, embodying my new design;

FIG. 2 is a top plan view thereof, with the chair in the position shown in FIG. 4;

FIG. 3 is a front elevation view thereof;

FIG. 4 is a side elevation view thereof, the opposite side being substantially the mirror image thereof; and

FIG. 5 is a rear elevation view thereof.

I claim:

The ornamental design for a folding chair, as shown and described.
